COMBINATION LOCK

Mathew Schnur, Chicago, Ill.

Application May 10, 1940, Serial No. 334,451

10 Claims. (Cl. 70—101)

My invention relates to combination locks, and more particularly to the type of lock covered in my Patent No. 2,118,478, dated May 24, 1938, and my main object is to improve the mechanism of the patented structure in a manner to control the functions of the lock more easily, with greater precision, and with more secrecy.

A further object of the improvement is to simplify portions in the mechanism of the lock, so that the latter is less expensive to produce and may operate efficiently and without need of frequent attention or repair.

Another object of the invention is to provide means to more definitely retain parts at given positions in their movements, so that such parts do not deviate or change such positions to the prejudice of the solution of the combination.

With the above objects in view and any others which may suggest themselves from the description to follow, a better understanding of the invention may be had by reference to the accompanying drawings, in which—

Fig. 1 is an elevation of the lock as viewed from the inner side of a safe door in which it is installed;

Figs. 2, 3 and 4 are, respectively, sections on the lines 2—2, 3—3 and 4—4 of Fig. 1;

Fig. 5 is a reproduction of a portion of Fig. 1, showing the positions of the parts when the combination has been solved;

Fig. 6 is a section on the line 6—6 of Fig. 1;

Fig. 7 is a section on the line 7—7 of Fig. 5;

Fig. 8 is a view similar to Fig. 1, showing a modification; and

Fig. 9 is a section on the line 9—9 of Fig. 8.

Referring specifically to the drawings, it is noted that the present combination lock follows the example of my patent by being incorporated in a safe door 20. However, the latter is now illustrated with an insulation filling 21 and an inner panel 22 also filled with insulation 23. This construction is in accord with conventional safe design, wherein insulation is employed for protection against fire. The door has an inner base plate 24 for the combination lock.

The improved lock retains the flush control feature recited in my patent, so that nothing projects from the door of the safe while the lock is not in use. However, the controls have now been vertically aligned near the hinge edge of the door, and have peculiar functions. Thus, the middle control is a button 25 initially employed to project an upper knob 26 from the door so that it may be operated by partial turns to solve the combination, in which event the button 25 may

be operated to retract the bolt 27, so that the door may be swung ajar by a spring or other suitable mechanism in the safe, as suggested in my patent. The bottom button 28 is operated when the door is closed and the combination is to be cleared, so as to lock the bolt 27. Of course, the button 28 may also function to clear the combination where its solution fails on any trial, and is again to be attempted.

The basic feature of the improved lock is quite similar to the one in my patent. Thus, the array of horizontal slide bars is again employed, the primary one being indicated at 29 and the secondary ones at 30. Thus, the step-by-step operation of the primary slide bar controls the selection of any desired secondary slide bar for its step-by-step advance toward the alignment of the slide bars in a given relation.

The slide bars are actuated by the knob 26. When this knob has been projected to be easily grasped between the fingers, its partial rotation in one direction will operate to advance the primary slide bar 29, and in the opposite direction to operate the selected one of the secondary slide bars 30. With the knob functioning in rotary directions, its movements can more easily be concealed than those of a push button, in case the combination is intended to be guarded from anyone who may be passing or watching. The shank 31 of the knob 26 carries a peripheral segment 32 whose ends are in front of the inner hooked portions 33 of a pair of levers 34 and 35. The lever 34 is pivoted to a stationary bracket 36 at 37, while the lever 35 is pivoted at 38 to a similar bracket 36a. A link 40 extends horizontally from a pivotal connection 41 at an intermediate point along the lever 34, while a similar link 42 is connected likewise to the lever 35 at 43. As in the patented structure, vertically aligned spindles 44 and 45 are located near the opening edge of the door, and the links 40 and 42 make free connections with the respective spindles by means of terminal eyes 46. The spindle 44 is carried by the arms 47 of a vertical frame 48 which is rockably disposed at its base in end brackets 49. The spindle 45 is similarly disposed in relation to a frame 50, so that both spindles are now movable laterally, and are drawn in a right-hand direction by springs 51 whose outer ends are secured to stationary fixtures 52.

In order to affect the segment 32, the projected knob 26 must engage the same for rotation. This is done by a side lug 39 at the rear end of the knob shank, this lug seating in a similar slot 39a in the segment when the knob is in the projected

position. Now, when the knob is turned in a counter-clockwise direction according to Fig. 1, it will be seen that the lug 39 will strike the lower end of the segment 32, causing the upper end thereof to bear on the hooked portion 33 of the lever 34 to swing the latter to the left; and the lever 35 will be similarly affected when the knob is turned in the opposite direction. These movements will have the effect of drawing upon the links 40 and 42 to move the spindles 44 and 45 toward the left. As in my patented structure, these spindles carry pawls 53 and 54 extending over the slide bars, these pawls being urged in the direction of the latter by springs 55 attached to heel portions 56 of the pawls. The primary slide bar 29 carries a cam plate 57 having the same function as the cam plate 50 in my patent to cause the secondary slide bars 30 to be selected by the pawl 53 in accordance with the movement of the primary slide bar 29, all precisely as in the patent. However, I have covered the greater portion of the slide bars by a plate 58 in order that the pawls 53 and 54 may only have access to the slide bar teeth by way of a limited opening 59. Thus, the recession of either pawl will cause it to be lifted by the plate to be clear of the slide bar teeth. I have provided no check pawls in the improved structure, preferring to dispose the slide bars between stationary separators 60 and outer guards 60a, so that the movement of one slide bar will not have a tendency to draw on the adjoining ones. As noted in Figs. 2 and 3, the body portion of the knob 26 is knurled for a secure hold and reduced in diameter in order not to rub along the walls of the socket 26a in which the knob is slidable.

As in my patent, the solution of the combination places the slide bars with a series of slots 30a in vertical registration. However, in the improved structure these slots are on the frontal sides of the slide bars and therefore not visible in Fig. 1. A control bar 61 is urged toward the stack of slide bars from the front and therefore falls into the aligned slots as soon as the combination is solved.

The fall of the control bar 61 in the manner suggested involves a mechanism originating with the middle button 25. This button has its shank 62 in contact with a finger 63 extending from a carrier 64 which is pivoted at 65 in a door bracket 66. The carrier journals a spindle 67 which becomes rockable laterally relative to the pivots 65, and is normally drawn to the left as seen in Fig. 1 by a spring 68 secured to a fixture 68a. A cross-bar 69 extends from a position shortly to the right of the spindle 67 to one at the extreme right as seen in Fig. 1. Here the end of the bar is pivoted as indicated at 70 to the shank 71 of the latch bolt 27. Thus, when the bar 69 moves to the right, the latch bolt is caused to recede by being pivoted intermediately in the lock case at 73.

The cross-bar 69 is normally urged rearwardly and also inwardly by a pair of springs 74 extending from a stationary plate 75 to a cross pin 76 passing through the bar. By being drawn inwardly the cross-bar pulls on the control bar 61 through the medium of an arch 77 passing from the latter around the cross-bar, so that when the alignment of the slide bar slots occurs, these afford clearance to the control bar 61, so that the latter may be drawn into the series of slots by the cross-bar 69 as just explained. However, this action will not occur until the button 25 has been given a partial push, so that the spindle 67 may

push a detent 67a toward the right as per Fig. 6. This detent has a head 67b cut with a shoulder 67c in its bottom, such shoulder normally resting on a corner of the control bar when the latter is in the outward or free position, an arch 67d maintaining the position of the detent on the bar. However, when the button 25 is pushed to advance the cross-bar 69, it is calculated to first push the detent 67a as stated, so that its shoulder 67c moves off the control bar, releasing the same for the inward movement, the parts now appearing as in Fig. 6. The control bar is secured to the door by a loose rivet 78 to permit its limited outward and inward motions.

The position of the cross-bar 69 affects its relation to the push button 25. Thus, the end of the cross-bar proximate to this push button receives a U-strap 79 whose sides are vertically spaced. This strap slidably houses in its bottom a hook 88 which is pivoted at its left-hand end as seen in Fig. 1 to a vertical stud 89 carried by the lower portion of a lever 90, the middle portion of such lever being pivoted at 91 to a fixture 92. The upper portion of the lever 90 is rounded toward the rear, so as to be tripped by the side lug 39 of the knob shank 31 when the knob is backed to the position shown in Figs. 2 and 3. The upper portion of the lever 90 is drawn toward the position alongside the knob shank by a spring 95 leading to the lower portion of the lever. The knob shank meets a frame 94 as a back stop and is tubular to house a compression spring 96 whose tendency is to urge the knob outwardly. This is done by simply pressing the middle button 25. With the parts located as in Fig. 2, it is seen that the effect of pushing this button is to move the spindle 67 toward the right, as explained before. The spindle will now impinge on the bill 88a of the hook 88—since the latter has been carried outwardly by the locked position of the cross-bar 69—so that the lever 90 is swung counter-clockwise on its pivot 91. The upper end of the lever will now back away from the lug 39, releasing the knob shank 31 for outward projection by the spring 96.

The action of the button 25 just described does not affect the cross-bar 69, and the pushing of the button cannot therefore retract the latch bolt 27 as long as the combination is unsolved. However, when the solution is attained, the control bar 61 finds inward clearance in the aligned slots 30a in response to the urge of the cross-bar from the pull of the springs 74. The cross-bar thus swings inwardly on its pivot 70 to back the hook bill 88a away from the spindle 67 and present the corresponding end of the cross-bar to the same. Now the advance of the spindle by the push of button 25 pushes the cross-bar to the right and retracts the latch bolt 27. When the button is released, the spring 68 serves to restore the same to its normal, flush position, while the springs 74 pull on the cross-bar 69 to restore the latch bolt 27 to the projected position. The lock may now be considered as open, and should the door 21 be closed, it may be opened by simply pushing the button 25 to withdraw the latch bolt, a suitable device such as shown at 23a in my patent then serving to push the door ajar.

Should it be desired to lock the door, the bottom button 28 is pushed, the shank 81 of the same serving to push a spindle 82 mounted precisely as the spindle 67 toward the right, as seen in Fig. 1. A link 83 from the spindle 82 swings a push bar 84 to the position indicated by dotted lines. As the slide bars 29 and 30 are directly in

the path of the push bar 84, the effect of the latter is to push them all back to the original position shown in Fig. 1. However, this cannot be done until the control bar 61 moves outwardly to emerge from the alined slots of the slide bars. Therefore, the push bar 84 acts before it meets the slide bars to propel a cam bar 85 pivoted to the push bar at 86 to press outwardly on the control bar 61, the cam bar being retained in its movement by a strap 81.

With the structural and functional characteristics of the mechanism explained, reference may be made to an early section in the above description where the operation of the lock is briefly described. As stated, the medial button 25 is the first one to be used when the combination is to be worked, the pushing of this button procuring the projection of the knob 26. The knob is next turned in one or the other direction as many times as the combination calls for, similarly to the alternative button control in my patent. When the end of the combination is reached, the pushing of the button 25 should release the bolt 27, so that the door may be opened. When the door is again closed and is to be locked, all that it is necessary to do is to push the lower button 28 with the effect of clearing the combination and locating the bolt in a manner not to be affected by the pushing of the button 25. Also, in case during the working of the combination that an error is made or the lock fails to open, the button 28 may be employed to clear the combination and make it possible to be worked again.

Figs. 8 and 9 show a modification whereby the lock may be operated by remote control. Thus, it may be desirable that a safe in a general office or establishment be controlled only by the executive, whose room may be in a different or remote part of the building. In such event, the knob 26 and its accessory parts may be dispensed with for the purpose of operating the bars 40 and 42 alternately. In the modified structure the counterparts of these bars are indicated at 100 and 101, and the alternate actuation of these in a left-hand direction for the operation of the slide bar group is induced by two push buttons (not shown) located handily in the room of the executive. By a suitable electrical circuit, the push buttons control solenoids 102 and 103 whose armatures are indicated at 104 and 105. The armature plungers 106 and 107 are directed toward levers 108 and 109 which are pivoted at 110 and 111 respectively. The lever 109 is connected directly to the spindle 45 by the bar 101. The connection for the lever 108, however, on account of the proper approach to the spindle 44, reaches the latter by way of a lever 112 connected to the bar 100, such lever being pivoted to the door base 24 at 113. A link 114 then extends from the lever 112 to the spindle 44.

The modification of Figs. 8 and 9 also shows means for actuating the spindles 44 and 45 from points in front of the door in case the electrical control fails. The means recited consist of push buttons 115 and 116 which operate the spindles precisely as do the buttons A and B in my patent, making a detailed description of the mechanism unnecessary.

It will be evident from the above description that the improved lock is not only simpler in many respects than the patented one, but also separates certain functional values by the provision of the control knob and the push buttons below the same. First, no buttons or controls are

necessary at both sides of the door. Second, the button 25 while serving mainly for advancing the cross-bar 69, also acts as a mechanism to project the combination knob 26. The latter has the single function of operating the combination; yet, it serves more handily for this purpose than a push button, and enables the combination to be kept secret, as mentioned before. The mechanism of the button 28 is ostensibly for combination clearing purposes, although it also provides a safeguard to clear the path for the return of the slide bars by assuring the outward clearance of the control bar 61 before the slide bars are actuated. Finally, the flush surface of the door is maintained despite the presence of the knob 26, as the latter may be pushed in and locked at any time that the work with the combination is over.

I claim:

1. Control means for a combination lock carried on the inner side of a door comprising, a control bar pivoted to the door and movable inwardly when the combination is solved, a bolt alongside the control bar and movable between outward and inward positions, an element controlling these positions to correspond with those of the control bar, a push button fitted in the door, and a member movable in the direction of the bolt when the button is pushed, the bolt being engageable by the member only when in the said inward position.

2. Control means for a combination lock carried on the rear side of a support comprising a knob and a push button set flushly at spaced points in the front of the support, means actuated when the button is pushed to project the knob from the front of the support for manual rotation, and connections from the knob to the lock to operate the combination, said means comprising a side projection at the rear end of the knob, a pivoted lever in front of the projection when the knob is in its rear position, a member movable laterally when the button is pushed, a hook carried by said lever to be engageable by said member with the effect of swinging the lever to withdraw it from its position in front of said projection, and a spring to project the knob forwardly when the projection is released.

3. Control means for a combination lock carried on the rear side of a support comprising a knob and a push button set flushly at spaced points in the front of the support, means actuated when the button is pushed to project the knob from the front of the support for manual rotation, and connections from the knob to the lock to operate the combination, said means comprising a side projection at the rear end of the knob, a pivoted lever in front of the projection when the knob is in its rear position, a member movable laterally when the button is pushed, a spring drawing said member in the opposite direction to resist the pushing of the button, a hook carried by said lever to be engageable by said member with the effect of swinging the lever to withdraw it from its position in front of said projection, and a spring to project the knob forwardly when the projection is released.

4. Control means for a combination lock involving vertically-spaced arms alternately movable in a given direction to operate the combination comprising, a rotatable knob intermediate the arms, a segment carried by the knob and adapted to be rotated with the same and upper and lower levers opposite the end portions of the segment and adapted to be singly moved by such

end portions in accordance with the direction in which the knob is rotated in harmony with the contemplated movements of said arms, said arms being connected to the respective levers.

5. The structure of claim 4, the segment being freely mounted on the knob, means to advance the knob to the projected position, and other means to connect the knob with the segment for joint rotation when the knob assumes the projected position.

6. Control means for a combination lock having a series of superimposed slide bars carried on the inner side of a door comprising a control bar pivoted to the door and outwardly positioned as long as the combination is not solved, means to move the control bar inwardly when the combination has been solved, second means to clear the combination, and third means operative before the second means is effective to return the control bar to the outward position.

7. Control means for a combination lock carried on the inner side of a door and having a series of superimposed slide bars with slots on their outward sides which register when the slide bars have been variously advanced to solve the combination, comprising a control bar pivoted to the door and positioned outwardly of the slide bars as long as the combination is not solved, means to move the control bar inwardly to seat in the aligned slots of the slide bars when the combination has been solved, second means to clear the combination by moving the slide bars back to their original positions, and third means operative before the second means is effective to eject the control bar from said slots, whereby to enable the slide bars to clear the control bar on their return movements.

8. The structure of claim 6, said third means comprising a pusher movable in the direction of the slide bars, an arm directed from the pusher to a position behind the control bar, such arm having its free end chamfered to climb the control bar on the advance of the pusher, and a retainer for the arm to constitute the free end of the same as a cam to push the control bar outwardly on the advance of the pusher.

10. 9. The structure of claim 1, a rotatable combination-control knob having an inward position flush with the front of the door when inactive, a lever normally locking the knob in the inward position, a hook connected to the lever and in 15 the path of said member when the bolt is in the outward position, the effect of the member's movement being to push the hook and draw the lever to unlock the knob, and means automatically advancing the knob to forward position 20 when so unlocked to project from the front of the door for manipulation.

10. The structure of claim 1, a rotatable combination-control having an inward position flush with the front of the door when inactive, a lever 25 normally locking the knob in the inward position, a hook vertically-pivoted to the lever, a strap holding the hook to the bolt and effective to swing the hook to be in the path of said member when the bolt moves from the inward to the outward 30 position, the effect of the member's movement being to push the hook and draw the lever to unlock the knob, and means automatically advancing the knob to forward position when so unlocked to project from the front of the door for 35 manipulation.

MATHEW SCHNUR.
